UNITED STATES PATENT OFFICE

150,500

DESIGN FOR A DISPLAY CONTAINER

Florence Perry Holden, Los Angeles, Calif.

Application July 29, 1946, Serial No. 132,076

Term of patent 7 years

(Cl. D80—9)

To all whom it may concern:

Be it known that I, Florence Perry Holden, a citizen of the United States and resident of the city of Los Angeles, county of Los Angeles, State of California, have invented a new, original, and ornamental Design for Display Container, of which the following is a specification, reference being had to the accompanying drawing, forming a part thereof, in which:

Fig. 1 is a front elevational view of a display container, showing my new design; and

Figs. 2 and 3 are side elevational and plan views, respectively, of the design as shown in Fig. 1.

I claim:

The ornamental design for a display container, substantially as shown.

FLORENCE PERRY HOLDEN.
